SPIRALLY CONTRACTIBLE AND EXPANSIBLE MOP-WRINGER SCRUB BUCKET ATTACHMENT WITH MEANS TO LIMIT EXPANSION

Edwin A. Strattman, New Orleans, La.

Application January 17, 1947, Serial No. 722,482

2 Claims. (Cl. 15—263)

1

The invention relates to mop wringers of the general type disclosed in my U. S. patent applications, Serial No. 621,890, filed October 12, 1945, now abandoned, and Serial No. 656,417, filed March 22, 1946, now Patent Number 2,447,917, in which a frusto-conical sleeve is formed from a resilient sheet suitably curved and having its ends slidably overlapped, the outer end being anchored and the inner end having means to be engaged by a handle-carried mop when said mop is inserted into the sleeve and rotated, thus causing spiral contraction of the sleeve to squeeze the mop.

One object of the present invention is to provide new and improved means for stably mounting the frusto-conical sleeve and for limiting its self-expansion to a predetermined normal diameter.

Another object is to provide the inner extremity of the sleeve with new and improved mop-engaging means which will prevent upward sliding of the mop on said means while said mop is being rotated to contract the sleeve.

A further object is to provide the inner end portion of the sleeve with dome-like mounds, which aid in holding the mop against upward sliding during sleeve contraction, and aid also in temporarily connecting the mop and sleeve during rotation of said mop to contract said sleeve.

Figure 1 of the accompanying drawing is a perspective view showing the wringer mounted in the upper portion of a scrub bucket.

Fig. 2 is a vertical sectional view on line 2—2 of Fig. 1.

Fig. 3 is substantially a horizontal sectional view on line 3—3 of Fig. 2.

Fig. 4 is a diagram showing the manner in which the sleeve is spirally contracted when a mop is inserted and rotated.

Figs. 5 and 6 are top views of a split band and a continuous band, respectively, either of which may be used in mounting the sleeve.

The preferred construction has been illustrated and will be rather specifically described, but variations may be made within the scope of the invention as claimed.

A one-piece, resilient, perforated sheet 7, preferably though not necessarily formed from spring steel, is curved to provide a frusto-conical sleeve 8 for disposition in the upper portion of an ordinary scrub bucket 9, with its larger end disposed upwardly. The inner and outer ends 10 and 11 of the sheet 7 overlap and slidably contact with each other, and the tension of said sheet is such

that the sleeve 8 is self-expanding to normal diameter, as seen in Figs. 1 and 3.

The outer end 11 of the sheet 7 is anchored by means hereinafter described, and the extremity of the inner end 10 is provided with a return-bend 12 for temporarily connecting said inner end 10 with a mop, when the latter is inserted into the sleeve 8 and rotated clockwise. This rotation of the mop thus causes contraction of the sleeve 8 to effectively squeeze surplus water from said mop.

The free edge of the return-bend 12 is formed with vertically spaced notches 13 which receive portions of the mop and prevent it from sliding up on said return-bend during rotation of said mop and sleeve contraction. To aid in preventing the mop from being pushed upwardly as the sleeve 8 contracts around it, and to also aid in temporarily connecting the inner end portion of the sheet 7 with the mop during rotation of the latter in sleeve-contracting direction, I provide said inner end portion with spaced, inwardly stamped, dome-like mounds 14.

I provide novel means for mounting the sleeve 8 and for preventing excessive expansion of said sleeve. This mounting means includes a bucket-engaging clamping means 15, and a sleeve-encircling band secured to said clamping means, said band being of the overlapped-end-form shown at 16 in Figs. 1 to 3 and 5, or of the continuous form shown at 16a in Fig. 6. The band 16 or 16a is preferably of metal and it snugly surrounds the sleeve 8 near its upper end, said band being tapered in agreement with the taper of said sleeve. The outer end 11 of the sleeve-forming sheet 7 is secured to the band 16 or 16a by means of a radially disposed bolt 17 which extends outwardly through these parts, said bolt having a thin head 18 between said end 11 and the end 10. Adjacent this head, the bolt 17 is provided with a square portion 19, and the bolt holes in the parts 11 and 16 (or 11 and 16a) through which said bolt extends, are shaped to fit said squared portion 19. See the openings 20 in Fig. 5 and 20a in Fig. 6. A C-shaped clamping member 21 is slidable on the bolt 17, and the upper end 22 of said member 21 overlies and rests on the upper edge of the band 16 or 16a, and abuts the outer side of the outer end portion 11 of the sleeve-forming sheet 7. The lower end 23 of the member 21 is shaped to engage the bucket rim as seen in Fig. 2. A wing nut 24 is threaded on the outer end of the bolt 17 and serves to tighten and loosen the clamping means.

When the device is positioned as seen in Figs.

1 and 2 and the nut 24 tightened, both the sleeve 8 and the band 16 or 16a are tightly held in place and cannot turn about the bolt 17, and said band will then aid materially in properly supporting said sleeve, as well as preventing excessive expansion of said sleeve. The band is of course sufficiently below the upper end of the sleeve 8 to prevent the latter from being downwardly sprung from engagement with said band when pushing the mop downwardly in said sleeve.

By simply pressing the mop downwardly in the sleeve 8 some of the water will be squeezed out and in some instances, this will be sufficient. However, for more intensive squeezing, the mop is rotated to spirally contract the sleeve as diagrammatically shown in Fig. 4: During this sleeve contraction, the sleeve tends to push the mop upwardly, but this is prevented by the notches 13 and the mounds 14.

From the foregoing and the accompanying drawing, it will be seen that novel provision has been made for attaining the desired ends, but attention is again invited to the possibility of making variations within the scope of the invention as claimed.

I claim:

1. A mop wringer comprising a resilient perforated sheet curved into the form of a frusto-conical sleeve having its larger end disposed upwardly, the ends of said sheet being overlapped and slidably contacting with each other to impart continuity to the side wall of said frusto-conical sleeve, said overlapped ends of said resilient sheet being free from attachment to each

other to permit spiral contraction of said frusto-conical sleeve and to allow said frusto-conical sleeve to be self-expanding to normal diameter after contraction, mounting means for said frusto-conical sleeve including a band surrounding and normally contacting with the upper end portion of said sleeve to limit the expansion thereof, and means securing only the outermost of the slidably overlapped ends of said resilient sheet to said mounting means, the innermost of said overlapped ends having inwardly projecting mop-engaging means to temporarily connect it with a mop, while rotating the latter in said sleeve in a direction to contract said sleeve.

15. 2. A structure as specified in claim 1; said mounting means including a bucket-engaging clamp to which said band is secured.

EDWIN A. STRATTMAN.
